UNITED STATES PATENT OFFICE.

THOMAS L. CHAPMAN, OF BONDSTVILLE, MASSACHUSETTS, ASSIGNOR TO DRAPER CORPORATION, OF HOPEDALE, MASSACHUSETTS, A CORPORATION OF MAINE.

FILLING-REPLENISHING LOOM.

Application filed January 6, 1923. Serial No. 611,154.

To all whom it may concern:

Be it known that I, THOMAS L. CHAPMAN, a citizen of the United States, residing in Bondsville, in the county of Hampden and State of Massachusetts, have invented an Improvement in Filling-Replenishing Looms, of which the following description, in connection with the accompanying drawings, is a specification, like characters on the drawings representing like parts.

This invention relates to filling replenishing looms, and more particularly to means for preventing portions of the filling extending from an ejected filling carrier after replenishment from being drawn into the shed.

In looms of the filling replenishing type, it is now the common practice to cut or sever the filling between the cloth selvage and the filling carrier to be ejected when the filling is to be replenished. Thus, when the filling carrier is ejected, a trailing end of filling extends from the ejected carrier through the shuttle eye and sometimes longitudinally of the shuttle box and is liable to be drawn into the shed when the shuttle is again picked and produce imperfect cloth. Many attempts have been made to prevent the trailing end of filling from being carried into the shed and some of these have provided mechanism for catching the filling between the ejected filling carrier and shuttle, while others have sought to withdraw the trailing end of filling. Such mechanisms, however, add to complication in the loom parts, or require structural conditions not always desirable.

In accordance with the present invention a very simple and effective means is provided for catching and holding the filling end between the ejected filling carrier and shuttle box, so that when the shuttle is picked such end will not be drawn into the shed, and consists of a brush which is mounted on the lay with its bristles or brush elements extending laterally of the passage-way for the ejected filling carrier to engage and hold the filling end. The bristles or brush elements are preferably yielding in order that they shall not present any effective obstruction to the passage of the ejected carrier, and may extend longitudinally of the shuttle box a sufficient distance to insure engagement of the filling regardless of the part of the filling carrier

from which the filling leads. In some cases it may be desirable to employ means for withdrawing the filling from the brush and shuttle, that the trailing end may not remain in the shuttle box or on the brush with the incident liability of being broken and drawn into the shed on subsequent picks of the shuttle.

The novel features and new combination of parts comprised by the present invention will be hereinafter described in connection with the accompanying drawings, which show a good practical form thereof.

In the drawings:

Fig. 1 is a perspective view at the replenishing side of the loom, having certain parts broken away, and showing features of the present invention;

Fig. 2 is an enlarged cross-sectional view through the shuttle box;

Fig. 3 is a plan view of the replenishing shuttle box with parts broken away to show other parts beneath; and

Fig. 4 is an enlarged perspective view of the replenishing shuttle box and showing the filling catching and holding brush extending into the passage-way for the filling carrier to be ejected.

In looms of the filling replenishing type which employ a feeler mechanism, replenishment is usually called prior to complete exhaustion of the filling in the running shuttle, and when the filling carrier or bobbin to be ejected is thrown from the shuttle in the replenishing box by the incoming full filling carrier it is passed downwardly into a receptacle beneath, but the end of the filling leading from the ejected filling carrier often still remains threaded through the shuttle eye and is liable to be drawn into the shed and form an imperfection in the cloth.

The replenishing mechanism, in accordance with the present invention, may be of any usual type, and as shown, comprises the hopper 1 in which a series of loaded filling carriers 2 are supported. The hopper 1 is rotated from time to time to place the filling carrier in position for transfer by call mechanism actuated on call for replenishment. The transference 3 is mounted on a rod or dead shaft 4 supported by the hopper stand, as usual, and has an arm 5 connected to a dog 6 for actuation of the transference by a bunter on the lay to effect replenish-

ment of filling. These parts may all be of any usual or desired construction.

The lay 7 is provided with a shuttle box 8 at the replenishing side of the loom 5 and has an opening 9 extending through the bottom of the shuttle box for the passage of the filling carrier to be ejected when replenishment of filling is effected. The shuttle 10 which carries the filling carriers 10 by the usual holding jaws is also provided with an opening 11 for the passage of the ejected filling carrier, and below the opening for the filling carrier is a chute 12 for directing the ejected filling carrier away 15 from the going parts of the loom and preferably into a can or receiver beneath. All the parts thus far described may be of usual construction.

In accordance with the present invention, 20 a brush is secured to the lay in such position that the bristles or brush elements extend transversely partially across the passage-way for the ejected filling carrier and since the bristles or brush elements are of a yielding 25 nature they form no obstruction to the free passage of the ejected filling carrier.

In the present instance of the invention, the brush consists of a bar 13 which extends longitudinally of and below the shuttle box 30 and is provided with a series of bristles or brush elements 14 which, as indicated in Figs. 2, 3 and 4, project into the opening or passage-way for the ejected filling carrier. The bar 13 is secured to the under side of the 35 shuttle box by screws 15, the construction being such that when a filling carrier is ejected from the shuttle, as indicated in Fig. 2, the ejected filling carrier 16 passes downwardly through the opening or passage-way 40 provided therefor and may come in contact with the bristles or brush elements 14 which extend into the passage-way, so that the filling end *a*, which extends from the ejected filling carrier through the shuttle eye 17, 45 will be engaged by the bristles or brush elements and frictionally hold the trailing end of the filling so that when the shuttle is again picked the trailing end of the filling will be held by the brush, and as the shuttle 50 is picked will cause the trailing end to be unthreaded from the shuttle eye and not carried into the shed.

When the filling has reached a degree of substantial exhaustion and the filling carrier 55 is ejected from the shuttle during the replenishing operation, the filling *a* may lead from different points longitudinally of the filling carrier, and to insure that the filling leading from the ejected filling carrier shall be engaged by the bristles or brush elements regardless of the position longitudinally of the filling carrier from which the filling end extends, the brush is preferably made of sufficient length longitudinally of the shuttle 60 box to engage the filling. As shown, the

brush is preferably formed of a length coincident or approximately equal to the filling bearing portion of the filling carrier, as best illustrated in Fig. 3.

It may sometimes be desirable to withdraw the filling entirely from the brush and shuttle box so that on subsequent picks of the shuttle the trailing end of the filling may not remain in position to be engaged by the shuttle or be liable to be drawn into the shed, 70 and to this end a filling end withdrawing device may be employed in connection with the thread catcher and holder. In the present instance the filling end withdrawing device comprises a toothed arm 18, Fig. 1, 80 extending longitudinally of the shuttle and having a forwardly projecting portion 19 adjustably connected by a bolt 20 and slot 21 to a carrier 22 which is itself mounted upon a stem or rod 23 projecting laterally from an arm 24 fixed to the stud or dead shaft 4. The arm 24 may be conveniently formed as a projecting member from the tip end support 25 for the filling carriers, but this is not, of course, necessary. The 85 position of the filling end withdrawing device is such that when the lay beats up and is in its front position, the portion 18 of the filling end withdrawing device enters the passage-way 9 formed in the lay, back of 90 the path of the outgoing filling carrier, as indicated in Fig. 2, so that as the lay goes back either on the replenishing or subsequent beats, the filling end withdrawing device is rendered effective to withdraw the 100 trailing end *a* of the filling from the brush and also from the shuttle box.

When filling replenishment is effected by the ejection of the filling carrier to be abandoned and the substitution therefor of a filling carrier containing a fresh supply, as indicated in Fig. 2, the ejected filling carrier passes downwardly through the bottom opening of the shuttle and the passage-way in the lay and shuttle box, forwardly of 110 the filling end withdrawing device 18, and the yarn bearing surface of the ejected filling carrier comes in contact with the bristles or brush elements 14 of the brush which extends into the passage-way. Owing to the 115 yielding character of the brush elements 14, as indicated in Fig. 2, they present no effective obstacle to the passage of the ejected filling carrier, and since the brush extends longitudinally of the shuttle box to an extent preferably approximate to the length of 120 the filling bearing portion of the filling carrier, it follows that the trailing end of the filling *a* from the ejected filling carrier will be engaged by the bristles or brush elements of the brush regardless of whether 125 the trailing end of filling is at the time near to or remote from the tip end of the filling carrier. When the shuttle is picked after having been replenished, the frictional 130

engagement of the bristles or brush elements with the trailing end holds the filling so that it is withdrawn from the shuttle eye, and on backward movement of the lay following replenishment, either immediately or subsequently, the filling end withdrawing device will withdraw the filling or trailing end from the brush and also from the shuttle box.

10 From the construction described it will be clear that the present invention provides a simple and effective means for preventing the trailing end of filling leading from an ejected filling carrier from being drawn into 15 the shed and that it is readily applicable to any of the usual types of filling replenishing looms without alteration therein or the addition of complicated mechanism.

The brush is preferably mounted on the 20 shuttle box below and at the front thereof, and the bristles or brush elements extend rearwardly into the path for the ejected filling carrier when replenishment is effected.

25 What is claimed is:

1. In a filling replenishing loom, the combination of the lay, a shuttle box having an opening for the discharge of a filling carrier, a brush mounted on the lay and intersecting 30 the path of the filling carrier as it is discharged from the shuttle to catch the filling and prevent it being drawn into the shed when the shuttle is again picked.

2. In a filling replenishing loom, the combination of the lay having a shuttle box provided with an opening for the discharge of a filling carrier, and a brush mounted on the lay below the shuttle box and projecting into the passage-way for an ejected filling carrier 40 to catch and prevent the filling leading from a discharged carrier from being drawn into the shed.

3. In a filling replenishing loom, the combination of the lay having a shuttle box provided with an opening for the discharge of a filling carrier, and a brush mounted on the lay in front of and below the shuttle box and projecting into the passage-way for an ejected filling carrier to catch and prevent 50 the filling leading from a discharged carrier from being drawn into the shed.

4. In a filling replenishing loom, the combination of the lay having a shuttle box and provided with an opening for the discharge 55 of a filling carrier, a brush mounted on the lay and having yielding bristles which ex-

tend into the passageway for an ejected filling carrier to engage the filling between the shuttle and an ejected filling carrier and retain it from being drawn into the shed when 60 the shuttle is picked.

5. In a filling replenishing loom, the lay having a shuttle box and provided with an opening for the passage of an ejected filling carrier, a brush mounted on the lay with the 65 bristles extending part way across the opening to engage the filling leading from an ejected filling carrier to the shuttle and prevent it from being carried into the shed.

6. In a filling replenishing loom, the lay 70 having a shuttle box and provided with an opening for the passage of an ejected filling carrier, a brush mounted on the lay with the bristles extending part way across the opening to engage the filling leading from an 75 ejected filling carrier to the shuttle and prevent it from being carried into the shed, and means for withdrawing the filling from the brush.

7. In a filling replenishing loom, the combination of the lay having a shuttle box and provided with an opening for the passage of a filling carrier when it is ejected from the shuttle, a brush secured to the lay and extending longitudinally of the shuttle box 80 with the bristles projecting laterally of said opening to catch and hold the filling between an ejected filling carrier and the shuttle box and prevent the filling end from being drawn into the shed. 85

8. A filling end controller for replenishing looms, comprising, in combination, a brush secured to the lay and having the brush elements or bristles extending into the passageway for the ejected filling carrier, and a filling end withdrawing device for engaging the filling between the ejected filling carrier and brush for withdrawing the filling end. 90

9. In a filling replenishing loom, the combination of the lay having a shuttle-box 100 with an opening for the discharge of a filling carrier, a brush secured to the lay and extending longitudinally of the shuttle-box for engaging the filling between the ejected filling carrier and shuttle, and a filling end 105 withdrawing device which engages the filling between the brush and ejected filling carrier and withdraws it from the shuttle-box and brush.

In testimony whereof, I have signed my 110 name to this specification.

THOMAS L. CHAPMAN.
